UNITED STATES PATENT OFFICE.

LOUIS HIRSCH, OF CINCINNATI, OHIO.

RAILROAD-CROSSING GATE.

Application filed June 14, 1926. Serial No. 115,911.

This invention relates to railroad crossing gates and has special reference to a train operated railroad crossing gate.

One important object of the invention is to provide an improved general construction for devices of this character.

A second important object of the invention is to provide improved and novel train controlled means for actuating a railroad crossing gate.

A third important object of the invention is to provide a novel arrangement of ratchet mechanism for holding the crossing gate closed until after a train has passed the crossing.

A fourth important object of the invention is to provide novel means for releasing the pawl and ratchet mechanism after the train has passed the crossing.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a plan view of a portion of a railroad track showing the general arrangement of the gate, the actuating mechanism, the pawl and ratchet device and the release therefor.

Figure 2 is a side elevation of such a portion of the track and disclosing the same parts as shown in Figure 1.

Figure 3 is a section on the line 3-3 of Figure 2.

Figure 4 is a section on the line 4-4 of Figure 1 but showing the gate expanded.

Figure 5 is a section on the line 5-5 of Figure 4 with the gate open.

Figure 6 is a diagram showing the general arrangement of the main parts of the device at a crossing, details being omitted.

In the present illustration of the invention there is disclosed a section of a railroad track having the usual pair of track rails 10 supported on ties 11. But one track is here shown but it will be obvious that the device may be used for a double track as well.

The roadway for vehicles is shown at 12 and is indicated as crossing the railroad at right angles although this invention can be

used with the vehicle road crossing the railroad at any angle.

It is to be noted that the vehicle road is omitted from all figures but Figure 6 in order to more closely assemble the working parts in Figures 1 to 5 as well as to show the device to a large scale. Reference is therefore to be had to Figure 6 for the proper general positions of the various elements.

We will first consider the train controlled gate actuating means, pass to the gate itself and then explain the release mechanism by which the parts are permitted to reassume their original positions.

Firmly fixed adjacent the railroad track at one side of the road is a post 13 whereon is pivotally mounted an arm 14 which extends towards the track normally at right angles thereto. This arm supports a rectangular casing 15 which is also braced to the post 13 by a brace arm 16 pivoted on said post. This casing is open at the bottom and slideable vertically in the casing is a gravity operated pawl member 17 which has its downward movement limited to clear a pair of arcuate ratchet bars 18 which normally are supported in horizontal position on a horizontal frame 19 fixed to the post 13. These ratchet bars are concentric to the post 13 and their adjacent ends are connected by inclined springs 20 to posts 21 fixed to the frame 19 so that with little effort these ratchet bars may be lifted above their normal positions so that they may be engaged by the pawl 17 upon movement of the casing 15 about the post 13. As will be seen from Figure 3 this casing projects over the track in such position as to be engaged by a bumper on a train running on said track.

In order to lift the ratchet bars there is provided on the inside of each rail a cam rail 22 with ends curved away from the adjacent rails. These cam rails are held against the track rails by coiled springs 23 but yield to move inwardly when the flanges of the train wheels move between them and the track rails. These cam rails are supported on a frame consisting of cross bars 24 and a longitudinal connecting bar 25. Fixed to the cam rail adjacent the post 13 are tie rods 26 which have their free ends each connected to one end of a lever 27 which is pivoted intermediate its ends to the frame 19, the other ends of said levers being connected to the respective ratchet bars

so that inward movement of the cam rail lifts these ratchet bars into position to be engaged by the pawl. Mounted on a stub shaft 28 carried by the frame member 25 is 5 a ratchet wheel 29 to which is pivoted a pair of tie rods 30 having their outer ends pivoted to the cam rails so that inward movement of the cam rails rotates this ratchet wheel. Mounted on the bar 25 is a pawl 31 10 which engages the ratchet to hold it from backward rotation and thus hold the cam rails in their inwardly moved position so that the ratchet bars will be kept raised. Thus when the cam rails are moved inwardly 15 and the casing swung around by the action of the train the parts will be held in such positions until the pawl 31 is released.

Extending from the post 13 and in the opposite direction to the arm 14 is an arm 20 32 to which is connected one end of a wire or cable 33 which normally extends vertically downward to the frame 19 and passes under a guide pulley 34 carried by said frame. Thus whenever the casing is swung 25 the cable will be drawn under the pulley 34 and stress on the cable will tend to restore the casing to its normal position.

Adjacent the side of the roadway 12 is a hollow post 35 wherein is a pair of plates 30 36 forced apart by a compression spring 37. The upper of these plates slides on a rod 38 extending centrally of the post and the upper plate is provided with lugs 39 which project through vertical slots 40 35 formed on opposite sides of the post. To one of these lugs is attached the cable 33 which passes over suitable guide pulleys 41 to the foot of the hollow post and then extends vertically of the post. The lower plate 40 is fixed and upon the cable being pulled by movement of the swinging arm 32 the upper plate will be drawn downwardly and will be there held so long as the arm 32 is prevented from swinging back to normal position 45 as previously described. When the pawl 17 is released the arm 32 is permitted to swing to normal and is caused to do this by the action of spring 37. The plates also have lugs 42, the lug of the upper plate 50 moving in a slot 43 and the lug of the lower plate resting on the bottom of said slot. To these lugs 42 is connected a lazy tong gate 44 of sufficient length to extend across the roadway when expanded. The outer or free end of this gate is supported on a roller 45. Now it can be seen that when the casing 15 55 is swung the gate 44 will be projected across and close the roadway.

The release mechanism comprises a cam 60 rail 46 which is mounted on a frame 47 to normally bear against a track rail 10, being there held by springs 48. This cam rail is located across the roadway from the previously described mechanism so that it is 65 only actuated by the train after the latter

has crossed the vehicle road. Attached to the cam rail is a bar 49 which is connected by a link 50 with a revolving drum 51. This drum has a cable 52 connected thereto and leading over suitable idlers 34 to the pawl 31 so that, as the cam rail 46 is pressed inwardly by the passing train the cable 52 will be drawn upon thus releasing the pawl 31 and permitting the previously described parts to return to normal positions. A cable 75 53 may also lead to one of the lugs 39 so that the spring 37 assists in restoring the drum 51 and cam rail 46 to normal positions.

If it be desired to operate a second gate across the track from the first gate, a cable 80 54 may be connected to the cable 34 and extend under the track to such gate. A spring 55 normally holds the pawl 31 engaged with the ratchet wheel 29.

The operation having been described in 85 detail it is merely necessary to state that a train in its passage strikes the casing 15 and swings it to close the gate. The gate is held closed until the train engages cam rail 46 which causes release of the gate closing 90 mechanism and permits the parts thereof to move to their normal positions.

There has thus been provided a simple 95 and efficient device of the kind described and for the purpose specified.

It is obvious that minor changes may be made in the form and construction of the invention without departing from the material spirit thereof. It is not, therefore, desired to confine the invention to the exact 100 form herein shown and described, but it is desired to include all such as properly come within the scope claimed.

Having thus described the invention, what 105 is claimed as new, is:

1. A crossing gate operating device including a swinging member normally extending into the path of a moving train, a pawl carried by the swinging member, a ratchet bar over which said pawl traverses, 110 said ratchet bar being supported for movement into and out of engagement by the pawl and being normally out of engagement therewith, train operated means for moving the ratchet bar into engaged position, a latch mechanism for holding the ratchet bar in said operative position, a train operated release for the latch mechanism, and an operative connection between the swinging member and a gate. 115

2. A crossing gate operating device including a swinging member normally extending into the path of a moving train, a pawl carried by the swinging member, a ratchet bar over which said pawl traverses, 120 said ratchet bar being supported for movement into and out of engagement by the pawl and being normally out of engagement therewith, a spring pressed cam bar in the path of the wheels of a train and movable 125 130

by said wheels against the spring influence, an operative connection between the cam bar and ratchet bar to move the latter to operative position upon movement of the cam bar by a train, a latch mechanism connected to the cam bar to hold the latter in train moved position, a train operated release for the latch mechanism, and an operative connection between the swinging member and a gate.

3. A crossing gate operating device including a swinging member normally extending into the path of a moving train, a pawl carried by the swinging member, a ratchet bar over which said pawl traverses, said ratchet bar being supported for movement into and out of engagement by the pawl and being normally out of engagement therewith, a spring pressed cam bar in the path of the wheels of a train and movable by said wheels against the spring influence, an operative connection between the cam bar and ratchet bar to move the latter to operative position upon movement of the cam bar by a train, a ratchet wheel revolubly mounted adjacent the cam bar, a link connected to the cam bar and eccentrically connected to said wheel, a pawl normally engaging the ratchet wheel, a train operated mechanism to move said last pawl out of engagement with the ratchet wheel, and means connected to the swinging member for operating a gate.

4. A crossing gate operating device including a swinging member normally extending into the path of a moving train, a pawl carried by the swinging member, a ratchet bar over which said pawl traverses, said ratchet bar being supported for movement into and out of engagement by the pawl and being normally out of engagement therewith, a spring pressed cam bar in the path of the wheels of a train and movable by said wheels against the spring influence, an operative connection between the cam bar and ratchet bar to move the latter to operative position upon movement of the cam bar by a train, a ratchet wheel revolubly mounted adjacent the cam bar, a link connected to the cam bar and eccentrically connected to said wheel, a pawl normally engaging the ratchet wheel, a second cam bar remote from the first bar but in the path of said train wheels for movement thereby, spring means yieldingly holding the second cam bar against movement, an operative connection between the second cam bar and second pawl, and means connected to the swinging member for operating a gate.

5. A crossing gate operating device including a swinging member normally extending into the path of a moving train, a pawl carried by the swinging member, a ratchet bar

over which said pawl traverses, said ratchet bar being supported for movement into and out of engagement by the pawl and being normally out of engagement therewith, a spring pressed cam bar in the path of the wheels of a train and movable by said wheels against the spring influence, an operative connection between the cam bar and ratchet bar to move the latter to operative position upon movement of the cam bar by a train, a ratchet wheel revolubly mounted adjacent the cam bar, a link connected to the cam bar and eccentrically connected to said wheel, a pawl normally engaging the ratchet wheel, a second cam bar remote from the first bar but in the path of said train wheels for movement thereby, spring means yieldingly holding the second cam bar against movement, a winding drum operatively connected to the second cam bar, a cable connecting the winding drum and second pawl, and means connected to the swinging member for operating a gate.

6. A crossing gate operating device including a swinging member normally extending into the path of a moving train, a pawl carried by the swinging member, a ratchet bar over which said pawl traverses, said ratchet bar being supported for movement into and out of engagement by the pawl and being normally out of engagement therewith, a spring pressed cam bar in the path of the wheels of a train and movable by said wheels against the spring influence, an operative connection between the cam bar and ratchet bar to move the latter to operative position upon movement of the cam bar by a train, a ratchet wheel revolubly mounted adjacent the cam bar, a link connected to the cam bar and eccentrically connected to said wheel, a pawl normally engaging the ratchet wheel, a second cam bar remote from the first bar but in the path of said train wheels for movement thereby, spring means yieldingly holding the second cam bar against movement, a winding drum operatively connected to the second cam bar, a cable connecting the winding drum and second pawl, an arm projecting from the swinging member, a gate post, a stationary plate carried by said gate post, a sliding plate carried by the gate post, a spring urging said plates apart, a lazytongs gate having the levers at one end connected to said plates, an arm projecting from the swinging member, and a cable connecting the arm and the movable plate and arranged to draw the movable plate toward the fixed plate upon movement of the swinging member from normal position.

In testimony whereof I affix my signature.

LOUIS HIRSCH.
